JOURNAL BOX CONSTRUCTION FOR RAILWAY CARS

James L. Ryan, 837 S. Pickwick St., Springfield, Mo., and
Arthur W. Nelson, Pompano Beach, Fla.; said Nelson
assignor to said Ryan

Filed Apr. 22, 1963, Ser. No. 274,871
21 Claims. (Cl. 308—40)

This application is a continuation-in-part of our application Serial No. 100,393, filed April 3, 1961, and allowed November 6, 1962, now abandoned.

The invention relates generally to improvements in journal box construction for railway cars, but relates more particularly to journal box constructions which include journal stops interposed between the axle journal and the journal box side wall, of which the James L. Ryan Patent No. 2,733,966 is an example.

Constructions embodying the features of the said Ryan patent have gone into extensive use and have proved to be a distinct improvement in the art. However, there are certain truck side frame journal box constructions which make it difficult or impossible to use cap screws, as contemplated in the said Ryan patent.

Also, there is a considerable number of journal boxes which embody the so-called waste retaining ledges. These ledges are so located and formed that they interfere with the application of journal stops of the construction disclosed in the aforesaid Ryan patent.

Heretofore there have been suggested journal stop constructions in which the securing means is located entirely within the journal box side walls. Such constructions avoid interference with structures externally of the journal box side walls and, hence, are advantageous for that reason. However, such constructions are open to one or more objections, such as possibly interfering with structures in the lower part of the journal box, being rather difficult to install, being of relative complex conformations and/or being relatively high in cost.

The general object of the present invention is to provide an improved journal stop construction such that it is held in place by means entirely within the journal box and which will avoid one or more of the objections to constructions of that general type as heretofore devised.

Another object of the invention is to provide a journal stop construction entirely within the journal box which can be applied to a wide variety of journal boxes, which shall be of simple construction, and which can be more easily assembled within the journal box.

Again it is an object of the invention to provide a journal stop arrangement of improved and simplified construction which can be applied to journal box constructions with or without the so-called waste retaining ledges.

It is also an object of the invention to provide a journal stop construction which will not interfere with the lubricating devices which are installed in the lower part of many journal boxes as a substitute for waste packing material which has previously been used, the parts of which can be made from standard rolled sections sheared to provide pieces of desired size, thus aiding in the reduction of the cost as well as simplifying installation.

A still further object of the invention is to provide a journal box stop construction which will provide a substantial horizontally disposed shelf on which the stop can be placed and against which the stop can be downwardly pressed, thus providing adequate support for the stop, whether the same be made of bearing metal or plastic.

Another object of the invention is to provide a journal stop construction with a spring member thrusting in a vertical plane against an overlying ledge and having portions thrusting the stop downwardly against an underlying

2

ledge, which will avoid critical tolerances, yet will be effective in operation, easy to install and low in cost.

The manner in which the above objects, as well as others, are attained will appear from the following description in connection with the accompanying drawings in which:

FIGURE 1 is a longitudinal vertical sectional view, through a railway car journal box, showing a preferred form of the invention as taken on the line 1—1 of FIG. 2;

FIG. 2 is a transverse vertical section on the line 2—2 of FIG. 3;

FIG. 3 is a transverse horizontal sectional view on the line 3—3 of FIG. 2, the bearing and wedge being omitted better to disclose underlying parts;

FIG. 4 is a top plan view of one of the journal stops illustrated in FIGS. 1, 2 and 3, but on a larger scale;

FIG. 5 is a vertical view, partly in section and partly in elevation, on the line 5—5 of FIG. 4;

FIG. 6 is a vertical sectional view on the line 6—6 of FIG. 4;

FIG. 7 is a fragmentary vertical transverse sectional view on the line 7—7 of FIG. 3, but on an enlarged scale, better to show the detailed shape of the associated parts;

FIG. 8 is a fragmentary view similar to FIG. 7 showing a modified construction, but on a scale larger than that of FIG. 7;

FIG. 9 is a fragmentary view on the line 9—9 of FIG. 8, but on a smaller scale, certain of the parts being broken away to show a vertical section for illustrative purposes;

FIG. 10 is an edge view of a bowed spring member of the type used in the various forms of the invention to provide thrust in a vertical direction in order to press the journal stop member firmly down upon the underlying supporting ledge or shelf, the same being on a scale substantially twice that of FIGS. 1 to 3, inclusive;

FIG. 11 is a face view of the spring member of FIG. 10 as viewed in the direction of the arrows on line 11—11 of FIG. 10;

FIG. 12 is a face view of a shim which may be used under certain conditions;

FIG. 13 is an end edge view of the shim shown in FIG. 12;

FIG. 14 shows the shim of FIGS. 12 and 13 in operative position on the journal box side wall;

FIG. 15 is a view similar to FIG. 9, but showing a modified construction;

FIG. 16 is a vertical transverse section on the line 16—16 of FIG. 15;

FIG. 17 is a top plan view of the journal stop shown in FIGS. 15 and 16;

FIG. 18 is a vertical view partly in section and partly in elevation of the journal stop of FIG. 17 and on the line 18—18 thereof;

FIG. 19 is an end elevational view of the journal stop as shown in FIGS. 17 and 18;

FIG. 20 is a detail fragmentary view as on the line 20—20 of FIG. 16, but showing a modified bracket construction for the spring, the spring being omitted for illustrative purposes; and

FIG. 21 is a view similar to FIG. 20 but showing a further modified construction of the bracket which the spring is designed to engage.

Referring now in detail to that embodiment of the invention shown in FIGS. 1 to 7, inclusive, and FIGS. 10 and 11, 30 indicates the journal box as a whole which is herein shown as being an integral part of the side frame 31 of a railway car truck. The journal box is of conventional construction and includes the upright side walls 32 which extend between the flat top or crown 33 and the rounded bottom 34. The upper part of the front end of the box is provided with an opening 35 which, in

practice, is closed by a cover, not shown. The rear end of the box has wall portions in which are spaced longitudinal openings 37 and 38, providing the dust guard groove 39. Each side wall 32 is formed between its ends with an integral hollow projection or column 40 that extends downwardly from the crown and then curves outwardly to merge at its bottom into the associated side wall of the journal box.

The purpose of these projections 40 is to provide abutments for engagement by parts of a journal bearing member 42 that includes a babbitt-like facing 43. Forty-one (41) indicates a wedge for the bearing member, the wedge being disposed between the bearing member and the top wall 33. At the front end thereof (see FIG. 1) is a lug 33' which acts as a restraining stop for the previously mentioned wedge of the journal box.

Part of an axle 45 is shown in broken lines in FIGS. 1 and 3, the same including a portion 46 of reduced diameter, from which extends the journal 47, the latter terminating at its outer end in an annular shoulder 48.

The structure described above is typical of the conventional journal box for use with the solid type journal bearing. In connection with the journal box, we provide a pair of lateral journal stops 50. The stops 50 are counterparts, and the means of holding them in place, are likewise counterparts. Therefore, a description of one of the stops and the co-operating elements for one side of the journal box will suffice for both.

The stop 50 is made of a material such that when engaged by the journal it will in no wise damage the smooth or external surface thereof. One of the stop members 50 is shown in FIGS. 4 and 5, detached from the journal box. As shown, the stop 50 is in the form of a generally elongated member comprising a body portion 51 with rearwardly projecting portions 52 and 53 at its ends. The projections 52 and 53 project rearwardly to a greater depth than the stop intermediate thereof, thereby providing a recess 54 to avoid interference with parts on the journal box side wall.

As shown, the stop member 50 has front and rear parallel vertical surfaces 51F and 51R and top and bottom horizontal surfaces 53' and 54'. As best shown in FIGS. 4, 5 and 6, it is preferable that the journal contact area of this face 51F be interrupted with one or more channels 51C to facilitate the flow of oil to the journal bearing when the surface is subjected to high unit pressure during operation of the brakes. If desired, however, the front face of the stop member may be without grooves or even curved on a radius the same as that of the journal.

The rear face 51R of the journal stop 50, as shown, is planar so that it can provide a substantial area of contact with the adjacent portion of the inner face of the journal box side wall.

The upper faces of the projections 52 and 53 are provided with grooves 100 and 101, respectively, the purpose of which will shortly appear. The ends of the grooves 100 and 101 terminate in upwardly extending projections 60 and 61, the purpose of which also will be clear from the assembly description.

Referring to the same views, the journal box side wall is provided with a shelf or ledge 65 which can be in the form of a conventional angle iron having one leg 66 welded or otherwise secured to the vertical side wall and the other leg 67 extending inwardly with its upper surface 68 in a horizontal plane. As is best shown in the larger view, FIG. 7, there is provided a U-shaped bracket member 69, having a vertical portion 70 and upper and lower horizontal leg portions 71 and 72, respectively. The latter is welded to the leg 67 of angle member 65 and the upper leg is welded to the adjacent portion 73 of the column 40.

As is clearly shown in FIGS. 1, 2, 3 and 7, the stop rests upon the upper face 68 of the angle member 65. Because of the recess 54 in the stop, there is no interfer-

ence with the bracket 69 or with the column 40 of the journal box side wall.

As is perhaps best shown in FIG. 7, there is a space 80 between the vertical portion 70 of the bracket 69 and the adjacent portion of the stop 50. Thus, should the journal engage the confronting face 51F of the stop in the operation of the car of which the journal is a part, the thrust will be against the journal box side wall and not against the bracket portion 70. This permits the bracket member 69 to be of relatively light section, since it need not resist powerful thrust forces generated when the journal shifts transversely of the journal box, as often obtains during operation.

In order to apply thrust in a vertical direction, there is provided a spring member 90 (shown on a larger scale in FIGS. 10 and 11). The spring 90 comprises an upwardly bowed central portion 91, a reversely curved end portion 92, a similar reversely curved portion 93, the latter terminating in a hook portion 94 which facilitates insertion and withdrawal of the spring.

Application of Journal Stops to Journal Box

Preparatory to applying the stop members 50, the brackets 69 have been applied to journal box side walls, as have the members 65. With journals 47 in position 25 in the journal boxes 30, the journal stop 50 is inserted from above. To do this it is necessary to jack journal box 30 to its highest position relative to the axle portion 46 to provide clearance to insert journal stop member 50 between journal 47 and projections 40. Member 50 is inserted into the box through the open front end thereof, which is of sufficient size to afford ample room for the entrance of the hands into the journal box. Member 50 is placed longitudinally of journal 47 with face 51F in contact with journal and moved downward past projection 40 and into position with the bottom 54' of the stop 50 resting on the face 68 of member 65. The projections 52 and 53 project toward and into contact with the journal box side wall. Relative longitudinal movement between the stop and the journal box is thus prevented. The spring member 90 is then moved into position, advancing the end 92 first through the first opening between the upright portion 70 of bracket 69 and the journal box side until the portion 92 of the spring 90 is positioned in the groove 100 of projection 52.

When the spring member 90 reaches its final position, the portion 93 thereof will be disposed in the groove 101 in projection 53. In moving into position the upwardly bowed portion 91 of the spring contacts the underside of the bracket portion 71, compressing the spring and exerting thrust in a vertical direction, which reacts to press the stop 50 down firmly on the seat formed by the face 68 of angle member 65. The projections 60 and 61 at the ends of grooves 100 and 101 prevent longitudinal movement of the spring 90.

It is believed that the construction and operation of the journal stop construction will be understood without further detailed description. However, some of the advantages thereof will be mentioned after a description of the modified forms of the invention as illustrated in other figures of the drawings.

The Modification Shown in FIGS. 8 and 9

The construction shown in FIGS. 8 and 9 is one in which the journal box side walls are provided with so-called waste retaining ledges. Except for slight variations, the journal stop member and the upright bracket member are like the construction first described. Similar parts have therefore been given the same numbers, but primed, and identical parts bear the same numbers. Thus 50' is the stop; 69', the bracket member, the bottom leg 72' of which rests upon and is welded to a bar member 67B which, in turn, is welded to the upper face L' of the waste retaining ledge L.

It will be noted that the lower portion of the vertical part 70' of bracket 69' is offset toward the adjacent jour-

nal box side wall. This permits the lower part of the stop 50' to be offset at 50L without engaging the bracket 70'. There is thus provided a thicker section for the stop, which provides additional strength which might be helpful, particularly with some materials.

While speaking of materials, it should be stated that the construction disclosed in this application is well adapted to the use of suitable plastics. As by way of illustration, nylon is a suitable plastic such, for example, as Du Pont's nylon known by the trade name of "Zytal No. 101," which weighs only about one seventh as much as a suitable bearing metal. Of course, plastic could be used in the form of the invention first described. Also, if desired the offset arrangement of the bracket 69 and the lower part of the stop in the form first described could follow the construction shown in FIG. 8, whether the stop be made of metal, plastic or other suitable material.

The manner of assembly of the construction of FIGS. 8 and 9 is the same, so no further description of that operation is required.

The Modification Shown in FIGS. 12, 13 and 14

Referring to FIG. 12, 110 is a shim of flat strip material having an offset portion 111 intermediate its ends. It is shown, in FIG. 14, assembled with a bracket member of the construction shown in FIGS. 1 to 3 and FIG. 7. The offset portion 111 clears the lower curved surface of column 40 and prevents vertical displacement while the end portions straddle the column 40. This construction accommodates the stop to undersize journals without the necessity of changing the dimension of the stop member 50.

The stop and spring have not been shown because the arrangement would be as before described, in which the spring forces the stop downwardly, the thrust being in a vertical direction or plane.

Further Comments

The journal stop constructions described afford a number of advantages over any heretofore suggested. The structure is entirely within the journal box. The bracket and the supporting shelf or ledge on which the stop is supported can be made of rolled sections sheared to form pieces of correct shape and size and require no forging or punching operations. This aids in the reduction of cost which is an important item to the railroads.

Also, in the present installation, providing for the spring thrusting in a vertical plane or direction against its top or upper surface does not involve restrictive tolerances as would be the case if the spring had to be projected through narrow passages and were to thrust in a horizontal plane. This is also a factor in keeping the cost of production low.

Another advantage of the disclosed construction, in which the spring thrust is in a vertical plane or direction with the spring ends bearing on the top face portions of the journal stop member and loaded by the bracket midway of the journal stop, permits the use of a relatively short spring as compared with other constructions, and, also, avoids the necessity of so close tolerances.

Again the shorter spring is of distinct advantage with respect to the application of and the removal of the spring from its operative position.

It will be noted that the spring is at a level above the center line of the journal and that, when insertion of the spring is started between the vertical portion 70 of the bracket 69, the outer end is well within the journal box. This avoids the close clearances involved in application and removal of longer springs where thrust is in a horizontal direction or plane substantially on the horizontal center line of the axle and the spring passes through a narrow passageway, the condition being such that when the inner end of the spring is entering the passageway in such constructions the outer end of the spring is in the bottom radius in the front opening into the journal box.

This situation is restrictive, generally, but is particularly restrictive with the journal box for 50-ton cars which constitute the highest percentage of cars presently in service.

To provide for the application of a retaining spring through a journal stop requires clearance, and when the application provides for spring thrust in a horizontal plane or direction the resistance to vertical play or movement of the stop within the magnitude of the clearance is merely the spring thrust times the coefficient of friction of the materials involved. However, with the construction disclosed in this application, the journal stop is held with the entire force of the spring against accelerating impacts from track irregularities.

In connection with the construction of FIGS. 8 and 9, it should be mentioned that in order to permit the journal stop to seat against the vertical side wall of the journal box, the triangular portion at each side of the bracket, corresponding to the triangular portion T (see FIG. 8) within the bracket, is removed as by grinding.

The Modification Shown in FIGS. 15, 16, 17, 18 and 19

In order to simplify an understanding of the modified construction, a prime (') has been added to the references which indicate similar parts in other views of the drawings; and where the parts are or may be the same, they bear the same reference characters. Thus, 32 is the side wall of the journal box and 40 is the conventional integral hollow projection or column.

The journal stop 50" is similar to the journal stop 50 as earlier described but, as will be explained, it is of modified construction, as compared to both stops 50 and 50'.

The stop 50" is supported on the shelf or ledge 65 which can be of the form of a conventional angle iron having one leg 66 welded or otherwise secured to the side wall 32 and the other leg 67 extending inwardly in a horizontal plane as before described in connection with those journal boxes which do not embody the so-called waste retaining ledge. When a waste retaining ledge is embodied in the journal box side wall, the journal stop support can be of the construction shown in FIG. 8. However, whether the journal stop support be of either form, it is provided with means interfitting with the stop to prevent relative longitudinal movement of the stop thereon. Thus, as shown in FIGS. 15 and 16, spaced members 67" rest upon and extend upwardly from the upper face of the angle iron portion 67. They are secured in place in any suitable way as by welding at 67W.

The spring bracket member 69" is of special construction and, as will appear shortly, it serves several functions. As shown, it comprises a portion 70" and a portion 71" which extends substantially at a right angle to the portion 70". The parts 70" and 71" are firmly secured together, as by welding, at 70W before the bracket is affixed to the journal box so that the bracket can be handled as a unit. When the bracket is in position, the portion 70" is vertically disposed, the upper part thereof being welded to the adjacent part of the column 40 at 70A and the inner part of portion 71" welded at 71A to the adjacent part of column 40.

By reference to FIG. 15, it will be seen that the bracket portion 71" is generally arcuate in shape and that the intermediate curved portion 91 of the spring 90 interfits with the underside thereof. The lower part of the portion 70" of the bracket 69" terminates a short distance below the intermediate portion 91 of the spring 90. As shown, the bracket portion 70" of the bracket terminates in a plane which is above the plane of the upper face of the journal stop 50".

The journal stop 50", as shown, is essentially an elongated piece of material of rectangular cross section except that in the upper rear central portion there is an elongated recess R defined by the vertical wall portions R¹, R², and R³, and the horizontal portion R⁴.

The wall portions R² and R³ of recess R are chamfered

at C where the wall portions R² and R³ intersect the rear face of the journal stop to facilitate placement of the stop into its operative position in the journal box and to clear the fillets at the intersection of the side walls of column 40 and the journal box side wall 32, and also where the wall portions R² and R³ intersect the top face of the journal stop to facilitate application of spring 90.

It will thus be seen that the journal stop 50" is of simple form so that it can easily be produced. Also, because in no place is the vertical section interrupted entirely from top to bottom, the stop possesses good strength or stability throughout. This feature is of especial advantage where the stop is to be made of a material, such as a plastic material, which does not have the strength of certain metals but which embodies characteristics that in other respects may be superior.

Application of Journal Stop of FIGS. 15, 16, 17, 18 and 19 to Journal Box

Preparatory to applying the stop member 50", the bracket 69" has been affixed to the journal box as before described. With the journal in position in the journal box, the journal stop is inserted from above the journal box having previously been jacked to its highest position relative to the axle portion 46 as before explained. With the construction shown in those forms of the invention illustrated in FIGS. 1 to 14, inclusive, the journal stop is assembled by inserting the journal stop from above and lowering it into position by moving the stop downward with its contact face 51^F against the journal and the legs 52 and 53 of the stop straddling column 40.

With the construction shown in FIGS. 15 to 19, inclusive, the journal stop will also be inserted from above, but in this case the bottom face 54' will be initially in contact with the journal instead of 51^F as before described. The journal stop is lowered and rotated outwardly directly under the spring bracket, recess R of the stop permitting rotation to bring contact face 51^F against the journal after which the journal stop is lowered upon its seat on the portion 67 of supporting member 65 to the position shown in FIGS. 15 and 16.

When the journal box is returned to its normal operating position, the journal stop is, of course, positioned between the journal and the adjacent journal box side wall so that any engagement of the journal with the contact face of the stop tending to move the journal stop outwardly is restrained by engagement of the rear face 51^R thereof with the journal box side wall thus preventing excessive movement of the journal laterally of the journal box as in constructions of FIGS. 1 to 14, inclusive, first described.

It will be noted that the interfitting arcuate or concave form of the bracket portion 71^X with the curved portion 91 of the spring prevents longitudinal movement of the spring relative to the spring bracket. Hence, the spring bracket forms a plurality of functions. The bracket, of course, enables the spring 90 to react therewith and exert thrust in a vertical plane or direction in order to press the stop downwardly into firm engagement with the supporting member 65. The bracket also serves to confine the spring as a whole against movement laterally inward of the journal box movement laterally outward being restricted by the adjacent journal box side wall. Finally, because of the shape of the bracket portion 70" and the shape of the intermediate portion 91 of the spring, relative longitudinal movement between spring and bracket is prevented after the spring has been inserted and has reached its operative position. This latter feature makes it unnecessary to provide formations in the upper face of the stop to prevent longitudinal movement of the spring. Hence, the upper face of the stop can be planar thus simplifying its formation.

The Construction Shown in FIG. 20

The only difference between the construction shown in

FIG. 20 and that shown in FIGS. 15 and 16 resides in the shape of portion 70^M of the bracket 69" which is similar to the portion 71^X of the form illustrated and described in connection with FIGS. 15 and 16. Instead of being arcuate in form, the portion 70^M comprises a member which is simply bent to provide two straight portions which extend downwardly from the central or apex portion. In this form contact between spring and bracket portion is primarily confined to the end portions of the bracket portion 70^M.

The arrangement shown in FIG. 21 differs from that of FIG. 20 in that the portion 70^M comprises a straight central portion 70^C and downwardly extending end wing portions 70^E. It is believed that the interfitting of the central portion of the spring therewith will be understood without further description.

It should be understood that the journal stop 50" in the arrangements shown in FIGS. 15 to 21, inclusive, could, if desired, be provided with grooves similar to the grooves 100 and 101 terminating in upstanding projections 60 and 61 as shown in FIGS. 4, 5 and 6. In such event the bracket portion 71^X need not be relied upon to prevent longitudinal movement of the spring and hence could be planar in a horizontal plane instead of being arcuate in shape. Also, if the spring brackets of the constructions shown in detail in FIGS. 7, 8 and 14 and the spring were formed to interfit to prevent longitudinal movement of the spring when in operative position, then the grooves 100 and 101 and projections 60 and 61 of the journal stop could be omitted. A number of interfitting construction for this purpose are illustrated in FIGS. 15, 16, 20 and 21.

From the foregoing it can be seen that a number of advantageous, unobvious results are obtained by the disclosed construction. Some have been referred to, and others will be appreciated by persons skilled in this art.

We claim:

1. The combination with a railway car journal box, including a crown, vertical side walls each having inner and outer faces and a bottom, of a horizontal railway car axle having an end part positioned in the journal box and which provides a journal portion, means providing a solid bearing between said crown and said journal portion, journal stop supporting means projecting inwardly from at least one of the vertical journal box side walls, and including a horizontal ledge portion, at least one journal stop positioned between the journal box side wall and said journal portion, said stop having an impact face normally out of contact with said journal portion and a portion overlying said horizontal ledge portion, bracket means comprising a portion extending inwardly in substantially a horizontal plane from the adjacent journal box side wall and above the plane of said horizontal ledge portion, said bracket means also including a downwardly extending leg spaced inwardly of the journal box side wall, the lower part thereof terminating adjacent said journal stop supporting means, and a longitudinally disposed spring having an upwardly bowed central portion disposed under and engaging said horizontal portion of said bracket means and being disposed between said downwardly extending leg and the journal box side wall, said spring having portions adjacent its ends engaging the journal stop, and being under stress exerting thrust in a vertical plane or direction, thereby pressing said journal stop downwardly into firm supporting engagement with the ledge portion of said journal stop supporting means.

2. The combination set forth in claim 1 in which said downwardly extending leg portion has its lower part offset toward the journal box side wall and in which the lower part of the journal stop has a portion offset in the direction of the journal box side wall to provide increased strength for the journal stop intermediate its ends.

3. The combination set forth in claim 1 in which the upper part of the bracket means is fixed to the journal

box side wall and the lower part is fixed to said journal stop supporting means.

4. The arrangement set forth in claim 1 in which a shim is positioned against the journal box side wall and in which the shim has a central upper portion extending inwardly and away from the journal box side wall and under the upper portion of said bracket means.

5. The combination with a railway car journal box, including a crown, vertical side walls each having inner and outer faces and a bottom, of a horizontal railway car axle having an end part positioned in the journal box and which provides a journal portion, means providing a solid bearing between said crown and said journal portion, journal stop supporting means projecting inwardly from at least one of the vertical journal box side walls, at least one journal stop positioned between the journal box side wall and said journal portion, said stop having an impact face normally out of contact with said journal portion and having a portion overlying said journal stop supporting means, and compression spring means operable to exert thrust in a vertical plane or direction and serving to press said journal stop means downwardly into firm engagement with said underlying journal stop supporting means, said compression spring means being removable in a horizontal direction whilst the journal stop rests upon the journal stop supporting means.

6. The combination with a railway car journal box, including a crown, vertical side walls each having inner and outer faces and a bottom, of a horizontal railway car axle having an end part positioned in the journal box and which provides a journal portion, means providing a solid bearing between said crown and said journal portion, journal stop supporting means projecting inwardly from at least one of the vertical journal box side walls, at least one journal stop positioned between the journal box side wall and said journal portion, said stop having an impact face normally out of contact with said journal portion and having a portion overlying said journal stop supporting means, and single spring means removable in a horizontal direction contacting longitudinally spaced portions of the journal stop and operable to exert thrust in a vertical plane or direction and serving to press said journal stop downwardly into firm engagement with said underlying journal stop supporting means.

7. The combination with a railway car journal box, including a crown, vertical side walls each having inner and outer faces and a bottom, of a horizontal railway car axle having an end part positioned in the journal box and which provides a journal portion, means providing a solid bearing between said crown and said journal portion, journal stop supporting means projecting inwardly from at least one of the vertical journal box side walls, at least one journal stop positioned between the journal box side wall and said journal portion, said stop having an impact face normally out of contact with said journal portion and having a portion overlying said journal stop supporting means, and means including a longitudinally disposed spring operable to exert thrust in a vertical plane or direction and serving to press said journal stop means downwardly into firm engagement with said underlying journal stop supporting means, said spring being removable whilst the journal stop rests in position on the journal stop supporting means.

8. The combination with a railway car journal box, including a crown, vertical side walls each having inner and outer faces and a bottom, of a horizontal railway car axle having an end part positioned in the journal box and which provides a journal portion, means providing a solid bearing between said crown and said journal portion, journal stop supporting means projecting inwardly from at least one of the vertical journal box side walls, at least one journal stop positioned between the journal box side wall and said journal portion, said stop having an impact face normally out of contact with said journal portion and having a portion overlying said journal stop support-

ing means, means projecting inwardly of the journal box side wall and in a plane above said journal stop supporting means, and a longitudinally disposed undulatory shaped spring overlying said journal stop, engaging said means inwardly projecting and being operable to exert thrust in a vertical plane or direction, thereby pressing said journal stop into firm engagement with the said underlying journal stop supporting means.

9. The combination set forth in claim 8 in which the spring has an upwardly bowed central portion and portions adjacent the ends thereof which engage portions of the underlying journal stop.

10. The combination set forth in claim 9 in which the journal stop and portions of the spring adjacent the ends are vertically offset interfitting portions.

11. The combination set forth in claim 10 in which the vertically offset portions comprise depressed portions in the upper side of the journal stop into which portions of the spring are received.

20 12. The combination with a railway car journal box, including a crown, vertical side walls each having inner and outer faces and a bottom, of a horizontal railway car axle having an end part positioned in the journal box and which provides a journal portion, means providing a solid bearing between said crown and said journal portion, journal stop supporting means projecting inwardly from at least one of the vertical journal box side walls in the form of a waste retaining ledge having an upper surface to which a member is affixed to provide a 25 seat for the journal stop, at least one journal stop positioned between the journal box side wall and said journal portion, said stop having an impact face normally out of contact with said journal portion and having a portion overlying said member affixed to said waste retaining 30 ledge, and means operable to exert thrust in a vertical plane or direction and serving to press said journal stop means downwardly into firm engagement with said underlying member supported on said waste retaining ledge.

35 13. The combination set forth in claim 12 in which a shim is positioned against the journal box side wall to compensate for journals of reduced size.

40 14. The combination set forth in claim 6 in which the journal stop is provided with formations above the bottom thereof which are formed and adapted to interfit 45 with said spring means to limit movement of the spring means longitudinally of the journal stop when the spring means is in assembled position on the journal stop.

45 15. The combination set forth in claim 7 in which the means including a longitudinally disposed spring operable to exert thrust in a vertical plane or direction and serving to press the journal stop downwardly into firm engagement with the underlying journal stop supporting means also includes bracket structure comprising a generally vertically disposed portion spaced inwardly of the 50 journal box side wall, which serves to prevent movement of the spring inwardly of the journal box side wall, and which terminates at its lower end in a horizontal plane substantially above the upper surface of the journal stop supporting means.

60 16. The combination set forth in claim 15 in which the lower end of said bracket portion terminates in a horizontal plane above the upper surface of the journal stop.

65 17. The combination set forth in claim 7 in which the means including a longitudinally disposed spring operable to exert thrust in a vertical plane or direction and serving to press the journal stop downwardly into firm engagement with the underlying journal stop supporting means also includes bracket structure with which interfits part 70 of the spring intermediate its ends, said bracket structure and spring part being formed and adapted to prevent longitudinal movement of the spring when in operative position in the journal box.

18. The combination set forth in claim 8 in which the said means projecting inwardly of the journal box

11

side wall is formed and adapted to interfit with an undulatory part of the spring, when the spring is in operative position in the journal box whereby longitudinal movement of the spring is prevented.

19. The combination set forth in claim 8 in which the said means projecting inwardly of the journal box side wall comprises two straight portions one extending downwardly and forwardly and the other downwardly and rearwardly of the journal box in positions adapted to engage said undulatory spring and prevent longitudinal movement thereof. 5

20. The combination set forth in claim 8 in which the said means projecting inwardly of the journal box side wall comprises a straight central portion extending longitudinally of the journal box and end wing portions ex- 10

15

tending downwardly therefrom being positioned to engage said undulatory spring and prevent longitudinal movement thereof.

21. The combination set forth in claim 15 in which the journal stop is formed with an upwardly and outwardly opening rear recess intermediate its length, the size of said recess transversely of the stop being less than the distance between the front and rear sides of the stop and the depth of the recess being less than the distance between the top and bottom sides of the stop thereby presenting a continuous section from front to rear sides below said recess for strength whilst permitting the placement of the stop into and its removal from its operative position in the journal box.
